HUBERT HERMANNS, OF BERLIN-PANKOW, GERMANY.

CASTING APPARATUS.

1,415,348.

Specification of Letters Patent. Patented May 9, 1922.

Application filed April 30, 1919. Serial No. 293,839.

To all whom it may concern:

Be it known that I, HUBERT HERMANNS, a subject of the German Emperor, and resident of Berlin-Pankow, Germany, have invented certain new and useful Improvements in Casting Apparatus, (for which I have filed applications in Germany May 8, 1917, and in Luxemburg Feb. 23, 1918,) of which the following is a specification.

10 In foundry works, especially in large steel works which operate according to the refining process in the open hearth as well as in such plants which employ the converting process, the casting according to the heretofore used processes offers great difficulties. This is due to the fact that the generally employed arrangements for the conveying of the ladles and for using their contents for casting have the drawback of being unable to raise the output or yield of the plant beyond a certain value. Among other things this is a feature which limits the quantitative increase of the charges for the converters and the furnaces, although such an increase considered for itself is much to be desired. Large individual yields, in order to secure a large total yield, require a smaller number of travels between the converting devices and the casting places. Especially when using the converter-process, which ordinarily employs a casting ladle travelling on the floor of the steel plant, the conveyance of the liquid steel to the casting places becomes difficult, by reason of the crossing of the wagons, of which one carries the filled ladle from the converters to the casting floor, while the other returns with the emptied ladle. This crossing of the wagons must be enabled by employing a switching stage. 40 This mode of operation results in a considerable loss of time and on account of the necessity of employing two to three casting wagons and a switching stage, causes a high first cost as well as high expenses for wages, power, repairs, interests and amortization. In addition to this there are various disadvantages connected with this process, such as intermittent operation of casting, large floor space for the steelworks and finally the 50 source of danger resulting from the casting wagon which travels through the foundry and from the recessed switching stage. In steelworks operating according to the process of refining in the open hearth, the difficulties are mainly overcome by the employment of several travelling cranes which for

this purpose are arranged at the same or at a different height. In this case likewise, it is impossible to avoid mutual interference of the travelling cranes and the first cost and operating expenses will also be high. Similar conditions are found in most foundries.

My invention is designed to obviate these difficulties, and more particularly in such a manner that the casting material is conveyed to the casting place by devices different from those performing the casting. A novel and essential feature of my invention consists furthermore therein, that the casting into the cast iron moulds is accomplished through a stationary casting device which is adapted to perform a swinging motion, whereby a travelling conveyance supplies the liquid casting material to said casting device, while the moulds are moved along said stationary casting device. It is advantageous to construct the casting machine in such a way that the one end of the fork holds the filled ladle, while a second ladle is held in the other end of the fork, and after having discharged its contents of cast steel into the cast iron moulds, will now let off the slag into especially provided slag wagons. By this I obtain the advantage that the work to be done by the wagons will be largely reduced and likewise the cost of construction and operation. Furthermore there will be less danger of accidents and in addition an essential increase of the casting capacity of the plant and continuity of service is secured.

90 In the accompanying drawing I have shown an example of carrying my inventions into effect with a steel plant operating according to the Thomas process. For purposes of this illustration, I have shown only two converters, *a* and *a'*, in the drawing, but the break in the plan view of the converter room between said two converters is intended to indicate that as many others as desired may be interposed therebetween. 100 The carrying wagon *b* travels on the track *c* which is arranged in the usual manner on the floor of the steel plant in front of the converters. For attaining greater safety of operation there is provided a further carrying wagon *b'*, which on the one hand serves as a reserve and on the other hand may be used for casting special ingots or for casting in a "team", that is casting from two sides, in the casting pit *l*. In the prolonged axis 105 of the track *c* there is mounted the stationary swinging device *d* for casting, said device 110

being equipped with the jibs or outriggers *e* and *f*. The casting device may be constructed according to the special operating conditions in various ways, for instance it 5 may be equipped with one or two jibs, with or without a lifting mechanism and as a rule with a contrivance for tipping the ladle. The ingots are cast in the known manner in cast iron moulds, or so-called chills, standing 10 upon the wagons, which latter are moved forward by means of a shifting mechanism *o* below the jib *e*. The empty moulds are conveyed to the casting places by any suitable vehicle on the track *h*. On the track 15 *g* the moulds together with their ingots are carried to the stationary stripper *i*, which may be operated hydraulically or electrically. The tracks *k* and *m* serve for the discharge of the slag from the ladles. The 20 prolonged track *n* running into the track *g* for the discharge of the ingots is an emergency track, which may be used in case of failure of the casting device *d*. The shifting machine *o* is operated from the stand 25 *p*. From the casting table *q* the casting of the ingots may be controlled. The operation will now be as follows. The carrying wagon coming from the converters *a* with the filled ladle is moved towards the jib *f* of 30 the casting machine *d* in such a manner that the jibs on either side will form an uninterrupted travelling path for the ladles. By means of a suitable shifting device the ladle is moved upon the jib *f* and a new ladle, 35 upon arrival, is hung into the jib of the carrying wagon through the crane, which serves for conveying the ladle. By this the carrying wagon *b* will be ready for the reception of a new charge. As soon as the ladle 40 resting upon the jib *e* is emptied, the casting device will be swung around an angle of 180 degrees, so that now the ladle suspended from the jib *f* will be positioned above the casting track, which enables the 45 casting to be started immediately. By the tipping mechanism for the ladles the slag, which is contained in an emptied ladle, will be discharged into a slag wagon, which travels upon a track *h* preferably arranged 50 below the floor of the plant, and thereupon the ladle is lifted through the ladle crane provided for this purpose. The cast ingots together with their moulds are conveyed upon the track by means of a shifting 55 mechanism *o* for the wagons to the stripper *i* and again moved back into the track *h*,

when in empty condition. The room for the moulds is equipped according to the demand with one or more ingot cranes of known construction for the exchange of the 60 moulds. For the case where the casting machine *d* becomes out of operating condition, the track *k* is connected through a prolonged part *n* with the track *g*. The casting may now be effected immediately through 65 the carrying wagon *b*, so that the operation of the plant may be maintained to a limited extent, especially since the reserve wagon *b'* will yet be available for carrying on the casting for a part of the steel production in 70 the casting pit *l*. The slag from the ladles is carried away upon the track *m*.

In a similar manner the casting process is carried out in steel works and other foundry plants having cranes travelling 75 upon a track in elevated position. In this case the cranes form solely the connecting link between the converting and smelting equipment and the plant for the casting proper.

Having thus described my invention, I desire to claim as new and to secure by Letters Patent:

1. In apparatus of the character described, the combination of a melting furnace, a 85 casting device, means for transferring ladles from said furnace to said casting device, a mold carrier and means for moving molds on said carrier to and from said casting device, a slag receiver movable to and from 90 said casting device, and means forming part of said casting device for positioning ladles selectively either over said mold carrier or over said slag receiver.

2. In apparatus of the character described, 95 the combination of a melting furnace, a casting device, a track between said furnace and said casting device, a ladle carrier movable on said track, a mold carrier and a track on which said carrier is movable to and from 100 said casting device, a slag receiver and a track on which said receiver is movable to and from said casting device, and means forming part of said casting device for positioning ladles selectively either over the 105 track on which said mold carrier is movable, or over that on which said slag receiver is movable.

In testimony whereof I have hereunto set my signature.

HUBERT HERMANNS.
